UNITED STATES PATENT OFFICE.

ERNEST A. WILLIAMS, OF CINCINNATI, OHIO, ASSIGNOR TO UNITED SHOE MACHINERY CORPORATION, OF PATERSON, NEW JERSEY, A CORPORATION OF NEW JERSEY.

HEEL-SEAT-FITTING MACHINE.

Application filed January 13, 1926. Serial No. 80,948.

This invention relates to stock-cutting machines and is illustrated herein as embodied in a heel-seat fitting machine arranged to skive surplus material from soles prior to 5 their attachment to shoes.

In the manufacture of shoes to which wood heels are to be attached, it is usual to trim surplus stock from the heel-seat portions of the soles of the shoes so as to reduce the area 10 of the heel-seats and to provide the shoes with heel-seats of a convex form corresponding to the concave or cupped attaching surfaces usually formed upon wood heels. This heel-seat fitting operation for a long time 15 was performed by hand but of recent years it has been increasingly performed by heel-seat fitting machines. Most of these machines have been organized to perform the heel-seat fitting operation after the soles 20 have been attached to the shoes and this today is the more generally used method, irrespective of whether the operation is performed by machine or by hand. However, there has recently been a tendency on the 25 part of some shoe manufacturers to perform the heel-seat fitting operation prior to the attachment of the soles to the shoes, this desire being based upon the possibility of reducing the manufacturing cost if the operation is 30 performed in this way.

It is an object of the present invention to provide a heel-seat fitting machine capable of operating upon soles prior to their attachment to shoes which will perform the heel-seat fitting operation with sufficient accuracy to satisfy the demands of manufacturers of the better grades of shoes, which can be operated at a low cost, and which will demand only a minimum of skill upon the 35 part of the operator.

In accordance with the foregoing the illustrated machine is provided with improved means arranged to deform the heel-seat portion of a sole so that its central portion lies 40 on one side and its peripheral portion lies on the other side of the surface to which the heel-seat is to be trimmed. Then, by relative movement of the deformed sole and a skiving knife or cutter the sole is trimmed 45 and beveled. Co-operating with the skiving knife or cutter is another knife arranged to make a pair of heel breast receiving cuts at the forward extremities of the trimming cut.

A feature of the invention comprises a

heel-seat fitting machine organization, for 55 example such as has just been outlined, including a holdown member or finger arranged to deform or to assist in deforming the stock and located during the fitting operation between a portion of the stock and 60 the skiving knife or cutter. As illustrated, the marginal portion of the heel-seat of the sole is engaged and supported by a plate or plates formed with a substantially U-shaped opening. A spring-pressed plunger 65 is located somewhat below this opening in position to engage the central portion of the heel-seat as the sole is deformed and to prevent excessive deformation. The holdown member or finger is arranged to clamp the 70 work in opposition to the plunger and positively to hold its central portion out of the path of movement of the knife or cutter, this finger being carried by a support out of the path of movement of the knife or cutter. 75 With the sole held in this manner the knife or cutter moves from the rear forward to the heel breast line, trimming the two edges of the sole simultaneously.

While the invention is described herein 80 with particular reference to a heel-seat fitting machine arranged to operate upon the heel-seats of unattached soles, it should be understood that it is not limited in its utility to such a machine. In various of its aspects 85 it is applicable to heel-seat fitting machines operating upon other than unattached soles and to cutting machines for operating upon other work pieces.

With the above and other objects and features in view, the invention will now be described with reference to the accompanying drawings and pointed out in the claims.

In the drawings,

Fig. 1 is a side elevation of a heel-seat 95 fitting machine embodying the present invention arranged to operate upon unattached soles;

Fig. 2 is a perspective view of the head of the machine of Fig. 1 with parts broken 100 away better to show the construction;

Fig. 3 is a perspective view illustrating the manner in which the heel seat portion of a sole is deformed prior to a trimming operation in the machine of Figs. 1 and 2;

Fig. 4 is a longitudinal section and Fig. 5 is a transverse section illustrating the trimming operation; and

Fig. 6 is a perspective view of the rear portion of a sole fitted by the illustrated machine.

The illustrated machine is provided with a column 10 near the bottom of which is journaled a power shaft 12 driven in any suitable manner, for example, by a belt driven pulley 14. Upon the shaft 12 are a plurality of cams arranged to operate the various moving parts of the machine. Pulley 14 is connected to these cams by a single revolution clutch which it is not necessary to describe in detail since it forms no part of the present invention, the clutch being controlled by a treadle 16. On the upper end of the column 10 is a head 18 carrying a work support 20, a horizontal slide 22 and an approximately vertical, angularly adjustable slide 24. Mounted upon the slide 22 is a skiving knife or cutter 26 and a lever 28 fulcrumed at 29 and carrying at its forward end a presser roll 30 arranged to apply pressure to the work in front of the knife 26 and to move forward so as to keep out of the way of the knife as the cut progresses. Carried also by the head 18 of the machine is a forwardly extending bracket or arm 32 having pivoted at 34 at its forward end a rearwardly extending bar 36, the depressed rear end of which is formed as an elongated holddown finger 38 arranged to engage the upper surface of the heel-seat of a sole to be operated upon and by pressure applied to finger 38 through roller 30 to force the upper surface of the central part of the heel-seat below the path of movement of knife 26. As illustrated, finger 38 has a flat upper surface for engagement with roller 30, a convex, work-engaging lower surface and a rounded end. To support the peripheral portion of the heel-seat of the sole and cooperating with finger 38 to deform the sole, are a pair of plates 40 shaped to provide a U-shaped opening beneath the heel-seat. These plates, as more fully shown in United States Letters Patent No. 1,307,285, granted June 17, 1919, on an application filed in the names of Samuel J. Wentworth and Frederick H. Perry, are pivotally supported at the rear and may be swung toward or from each other under the control of a treadle, herein numbered 42, from which they are operated through connections including a treadle rod 44. Carried by plates 40 are a pair of gage blocks 46 arranged to engage the edges of a sole to be operated upon somewhat forward of the heel breast line and thereby to limit the movement of plates 40 toward each other as treadle 42 is released. These blocks are located a short distance from the edges of plates 40 in accordance with the amount it is intended to reduce the heel-seat portion of the sole. Further forward on plates 40 are a pair of spring-pressed plungers 48 arranged similarly to

engage the edges of the sole and yieldable to accommodate soles of different shapes. As illustrated, these two plungers together present a divergent opening to facilitate the introduction of soles between them. The forward ends of plates 40 rest upon the work support 20 which serves to support the ball portions of the soles operated upon and is formed with a surface 50 underlying and supporting the ends of plates 40 so as to permit horizontal movement of plates 40.

Beneath the U-shaped opening formed in plates 40 is a spring-pressed plunger 52 having an enlarged head 54 arranged yieldingly to support the central portion of the heel-seat so as to prevent undue distribution of the sole. As illustrated, plunger 52 is housed in a sleeve 56, the lower end of which is closed by an adjustable screw 58 so that the resistance of spring 60 to the depression of the plunger may be adjusted. A stop screw 62 is arranged to engage the underside of the head 54 of plunger 52 positively to limit its downward movement. Thus, it will be seen that the central portion of the heel-seat which is located between finger 38 and the head 54 of plunger 52 is securely clamped as roll 30 moves down into engagement with finger 38 and is held so clamped as roll 30 moves forward in front of knife 26 during the trimming operation. As an added insurance against displacement of the work under the action of the knife 26 finger 38 is provided on its under surface with a projection or spur 64 (Figs. 4 and 5) arranged to be forced into the material of the heel-seat so as to give finger 38 a more positive grip thereupon.

To make a pair of heel breast receiving-cuts at the forward extremities of the trimming cut, for example as shown at 66 in Fig. 6, the machine is provided with an adjustable knife illustrated as comprising a pair of adjustable blades 68 carried by slide 24 adjustable and operable from one of the cams upon shaft 12 in the manner set forth in said United States Letters Patent No. 1,307,285. In order to prevent injury of knife-blade 68 by finger 38, the latter may be notched as shown at 75 in Fig. 2.

Means for adjusting plates 40 forwardly and rearwardly in accordance with the length to which the heel is to be trimmed may be provided as shown in said United States Letters Patent No. 1,307,285, this adjusting means being controlled by a hand lever 68 having a spring plunger movable into engagement with any one of a series of holes 70 formed in a bracket 72. Means for operating slide 22 to cause the reciprocation of knife 26 and for operating roll 30 to move it down, thereby holding the central portion of the work beneath the path of movement of knife 26 until knife 26 reaches the work and for thereafter moving roll 30 forward while

still in its lowered position, may also be provided, just as described in said United States Letters Patent No. 1,307,285, except, of course, that roll 30 engages the upper surface of finger 38 instead of bearing directly on the work.

To facilitate the lengthwise presentation of the soles to be operated upon, plates 40 are provided with a conspicuous mark, illustrated at 80 in Figs. 2 and 3, positioned at right angles to the length of the soles to be operated upon and extending transversely across the path of movement of knife 26. It is only necessary then, in order properly to position the soles to present them with their rear ends in alinement with line 80 and with their shanks in engagement with gage blocks 46. Plungers 48 bearing upon opposite edges of the sole will prevent any angular derangement while, at the same time, yielding to compensate for variations in the widths and shapes of the soles. As has been previously stated, variations in the lengths to which the heel-seats are to be trimmed are taken care of by adjustment of lever 68.

In the operation of the machine treadle 42 is depressed to spread plates 40 apart and the sole to be operated upon is placed upon plates 40 with its rear end in alinement with mark 80 and with its shank and forepart between gage-blocks 46 and plungers 48, respectively. Treadle 42 is then released, whereupon plates 40 move together until blocks 46 engage the sole. Then, bar 36 and finger 38 are depressed so that finger 38 engages the sole and the machine is started by stepping upon treadle 16. This causes slide 22 to move forward and roll 30 carried by lever 28 to move down, thereby pressing finger 38 forcibly against the sole and deforming the latter so that finger 38 and the upper surface of the central portion of the heel-seat are below the path of movement of knife 26 while the peripheral portion of the heel-seat is above the path of movement of the knife, being supported by plates 40. Knife 26 moves forward, trimming and beveling the periphery of the heel-seat, operating first upon the rear of the heel-seat and then upon its two edges simultaneously, and when it has almost reached roll 30, the latter also moves forward holding finger 38 out of the way of the knife. When knife 26 has reached the heel-breast line, it is withdrawn as also is roll 30. Then knife 68 is reciprocated to make the heel-breast cut and to sever the peripheral chip from the sole, leaving the heel-seat as shown in Fig. 6.

Having thus described my invention, what I claim as new and desire to secure by Letters Patent of the United States is:

1. A stock-cutting machine having a knife movable in a rectilinear path, and work-deforming means arranged positively to hold different parts of the stock on opposite sides

of the path of movement of the knife, said deforming means including a hold-down member arranged during the cutting operation to lie between the knife and a portion of the stock.

2. A stock-cutting machine having, in combination, a knife, stock-deforming means, means for causing relative movement of the knife and the deforming means whereby the knife is caused to cut surplus material from the deformed stock, said stock-deforming means including a member positioned between the stock and the knife during the cutting operation positively to hold a portion of the stock away from the knife, and means travelling along said member to hold said member out of the way of the knife.

3. A stock-cutting machine having, in combination, a knife, stock-deforming means, means for causing relative movement of the knife and the deforming means whereby the knife is caused to cut surplus material from the deformed stock, said stock-deforming means, including a thin hold-down finger arranged to assist in the deformation of the stock and positioned between the stock and the knife during the cutting operation, and a roll arranged to move along the finger in front of the knife thereby holding the finger out of the way of the knife.

4. A skiving machine having a yielding work-engaging member, a hold-down member arranged to clamp a work piece against said yielding member, a skiving knife, and means for causing relative movement of the work piece thus held and the skiving knife to cause the knife to perform a skiving operation upon the work piece, said hold-down member being held stationary during the skiving operation between the skiving knife and a portion of the work piece.

5. A skiving machine having means for deforming a work piece, a skiving knife, means for causing relative movement of the work piece and the knife to cause the knife to perform a skiving operation upon the work piece, said deforming means including a hold-down member positioned during the skiving operation between the skiving knife and a portion of the work piece, and means carried by said member arranged to be forced into the material of the work piece to provide positive engagement of the hold-down member with the work piece.

6. A skiving machine having a skiving knife, means for causing relative movement of the work piece and the knife to cause the knife to perform a skiving operation upon the work piece, means for deforming the work piece including a thin finger positioned during the skiving operation between the skiving knife and a portion of the work piece to hold that portion of the work piece from the knife, and a spur carried by said

finger arranged to be forced into the material of the work piece to provide a positive engagement of the finger with the work piece.

5 7. A heel-seat fitting machine having means for supporting the edge of the heel-seat portion of a sole, a knife, means for causing relative movement of the sole and the knife to cause the knife to trim surplus stock from the periphery of the heel-seat of the sole, and a holdown member arranged to be held stationary during the trimming operation between the knife and the central portion of the heel-seat of the sole and operating with the supporting means to deform the sole.

8. A heel-seat fitting machine having means for deforming the heel-seat portion of a sole, a trimming knife having a cutting edge arranged to operate simultaneously on both edges of the heel-seat of the sole, said deforming means including a holdown member arranged to be positioned during substantially the entire trimming operation between the knife and the central portion of the heel-seat of the sole, and means for causing relative movement of the deformed sole and the knife in the direction of the length of the sole to cause the knife to trim surplus stock simultaneously from the two edges of the periphery of the heel-seat of the sole.

9. A heel-seat fitting machine having a work support, a cutter arranged to trim surplus material from the peripheral portion of the heel-seat of a sole carried by the work support, and a holdown member, stationary during the trimming operation, having a sole-penetrating portion formed and arranged to engage the heel-seat of a sole operated upon securely to hold the sole against movement as the trimming takes place.

10. A heel-seat fitting machine having a work support with an approximately U-shaped opening therein, arranged to engage one side of and to support the peripheral portion of the heel-seat of a sole, an elongated finger arranged to engage the opposite side of the heel-seat of the sole supported by said work support, means movable lengthwise of said finger arranged to press the finger forcibly against the sole thus supported, and a cutter movable with said last-named means to trim surplus material from the periphery of the heel-seat of the sole.

11. A heel-seat fitting machine having a work support with an approximately U-shaped opening therein, arranged to engage one side of and support the peripheral portion of the heel-seat of a sole, an elongated finger arranged to engage the opposite side of the heel-seat of the sole supported by said work support, means movable lengthwise of said finger arranged to press the finger forcibly against the sole, and a knife movable

with said last-named means in a path clearing the side of the finger away from the sole to trim surplus material from the periphery of the heel-seat of the sole.

12. A heel-seat fitting machine having means for engaging one side of and supporting the peripheral portion of the heel-seat of a sole, a finger engaging the opposite side of the central portion of the heel-seat of a sole thus supported, a knife movable lengthwise of the sole to trim surplus material from the periphery thereof, and means arranged to move in front of the knife and engaging the finger to force the finger against the sole and out of the path of movement of the knife.

13. A heel-seat fitting machine having means for engaging one side of and supporting the peripheral portion of the heel-seat of a sole, a finger engaging the opposite side of the central portion of the heel-seat of a sole thus supported, a knife movable lengthwise of the sole to trim surplus material from the periphery thereof, and a roll movable in front of the knife and engaging the finger to force the finger against the sole, between the path of movement of the knife and the sole.

14. A heel-seat fitting machine having a work support with an approximately U-shaped opening therein arranged to engage one side of and to support the peripheral portion of the heel-seat of a sole, a member arranged to engage the opposite side of the heel-seat of the sole supported by said work support, a spur carried by said member, means for forcing the member against the sole thereby causing the spur to penetrate the sole so as to prevent lengthwise movement of the sole during the fitting operation, and a cutter arranged to trim surplus material from the periphery of the heel-seat of a sole thus held.

15. A heel-seat fitting machine having a work support with an approximately U-shaped opening therein arranged to engage one side of and to support the peripheral portion of the heel-seat of a sole, a member arranged to engage the opposite side of the heel-seat of the sole supported by said work support, a projection carried by said member, a knife movable lengthwise of the sole to trim surplus material from the periphery of the heel-seat thereof, and means for forcing said member against the work thereby causing the projection to penetrate the sole so as to prevent lengthwise movement of the sole.

16. A heel-seat fitting machine having a cutter, means for causing relative movement of the cutter and a sole to cause the cutter to trim surplus stock from the periphery of the heel-seat of the sole, a holdown member arranged to engage the central portion of the heel-seat and to be positioned during the

trimming operation between the cutter and the central portion of the heel-seat of the sole, and a knife arranged to make a heel-breast-receiving cut at the forward ends of the trimming cut.

17. A heel-seat fitting machine having means for trimming surplus material from the periphery of the heel-seat of a sole, and an elongated holddown finger arranged to assist in the deformation of the sole to be operated upon, said finger having a convex

sole-engaging surface and a flat surface formed to permit movement of the trimming knife thereover.

18. A heel-seat fitting machine having a holddown finger comprising a thin, elongated member convex on its work-engaging surface and flat on its opposite surface and with its end toward the rear of the shoe rounded.

In testimony whereof I have signed my name to this specification.

ERNEST A. WILLIAMS.
